UNITED STATES PATENT OFFICE.

HERMAN E. MALAIER AND FRANK R. CLARK, JR., OF ROCK MART, GEORGIA.

AUTOMATIC BOILER FEEDER.

Application filed December 6, 1921. Serial No. 520,232.

To all whom it may concern:

Be it known that HERMAN E. MALAIER and FRANK R. CLARK, Jr., citizens of the United States of America, residing at Rock Mart, in the county of Polk and State of Georgia, have invented new and useful Improvements in Automatic Boiler Feeders, of which the following is a specification.

The object of the invention is to provide a simple and directly controlled boiler feed mechanism adapted for operation under conditions insuring the maintenance of a substantially uniform depth of water in the boiler and free from exposure to interference in the performance of its functions by collateral conditions of the boiler; and with these objects in view the invention consists in a construction and combination of parts of which a preferred embodiment is shown 20 in the accompanying drawings, wherein:—

Figure 1 is a view partly broken away of a boiler feeding mechanism embodying the invention.

Figure 2 is a sectional view in detail of 25 the feed nozzle.

Figure 3 is a transverse sectional view of the nozzle taken in the plane of the valve.

Figures 4 and 5 are detail sectional views 30 respectively on the planes indicated by the lines 4—4 and 5—5 of Figure 2.

Figures 6 and 7 are detail sectional views on the planes indicated respectively by the lines 6—6 and 7—7 of Figure 3.

The apparatus consists of a feed nozzle 35 10 inserted in the wall or shell of the boiler 11 at any convenient portion of the upper-side thereof and provided at an intermediate point in its length, which is preferably reduced as indicated to minimize the extent 40 of opening in the wall of the boiler, with a suitable joint 12, said nozzle being of a three-way or three-channel type with its terminals preferably enlarged as shown but with its outer and inner members 10^a and 45 10^b consisting preferably of castings of respectively integral construction.

At the enlarged inner end of the inner member there is provided a transverse valve seat 13 in which is fitted a rocking valve 14 50 or its equivalent, provided with a port 15 for connecting the terminals of two of the passages, 16 and 17 which are designed for use as steam passages and are respectively in communication through pipes 18 and 19 55 with the steam dome 20 and the valve chest 21 of the pump indicated at 22, suitable cut-

off valves 23 and 24 being provided in said pipes. Said valve 14 also is provided with a port 26 for establishing communication between the remaining channel 27 and the water outlet 28 of the nozzle, said water channel being in communication by the feed pipe 29 with the pump for the supply of water to the boiler. The valve is controlled by float 30 connected with an arm 31 having 60 a yoke 32 which is terminally attached to the extremities of the valve. When the water in the boiler is at the prescribed level the valve is maintained in the closed position by the position of the float, and when 65 the level of the water in the boiler falls to an extent sufficient to justify replenishing, the ports of the valve will be opened to establish communication between the steam dome of the boiler through two of the channels in the nozzle and the steam or valve chest of the pump, and between the pump through the third channel of the nozzle with the outlet 28. Thus a direct control of both 70 the steam and water inlet is effected by a common valve of which the position is determined by the level of the water in the boiler, as distinguished from those conventional types of boiler feeders, where the steam and water pipes leading respectively from 75 the valve chest and the water outlet of the pump communicate respectively with the steam dome and a feed water nozzle terminally submerged in the liquid contents of the boiler, and which latter arrangement is 80 attained in practice with a degree of uncertainty of operation which is entirely eliminated by the mutual control of the steam and water channels through the agency of 85 a single valve as herein provided.

Having described the invention, what is claimed as new and useful is:—

1. A feed water apparatus for boilers having a three-way nozzle provided with a plurality of steam channels for respective connection with the boiler steam dome and the steam chest of the feed water pump, and another channel in communication with the pump and provided with a water outlet at the inner end of the nozzle, and a float actuated valve for controlling said outlet and the communication between said steam channels.

2. A feed water apparatus for boilers having a three-way nozzle provided with a plurality of steam channels for respective connection with the boiler steam dome and

the steam chest of the feed water pump, and another channel in communication with the pump and provided with a water outlet at the inner end of the nozzle, and a 5 float actuated valve for controlling said outlet and the communication between said steam channels, said nozzle consisting of separable inner and outer members for ar-

angement respectively within and outside of the boiler and being connected by a union 10 adjacent to the wall of the boiler.

In testimony whereof they affix their signatures.

HERMAN E. MALAIER.
FRANK R. CLARK, JR.
